UNITED STATES PATENT OFFICE.

JOHN D. OLcott, OF NORWALK, OHIO.

HORSESHOE.

No. 849,080.

Specification of Letters Patent.

Patented April 2, 1907.

Application filed February 27, 1906. Serial No. 303,210.

To all whom it may concern:

Be it known that I, JOHN D. OLcott, a citizen of the United States, and resident of Norwalk, county of Huron, State of Ohio, have 5 invented certain new and useful Improvements in Horseshoes, of which I hereby declare the following to be a full, clear, and exact description, such as will enable others skilled in the art to which it appertains to 10 make and use the same.

The invention relates to a horseshoe and casing formed of a flanged plate having one or more legs or flanges.

The objects of the invention are to provide 15 a form of horseshoe such that hardened calks can readily be attached thereto, and thereby a harder material can be employed out of which to form the calks than it would be practical to weld to the shoe and harder than 20 the material forming the shoe, and which also can be detached from the shoe for sharpening and replaced without removing the shoe from the horse's foot.

A further object is to form a shoe-casing 25 to which the calks can be conveniently secured or within which a detachable tread-plate can be secured to which the calks are attached.

I am aware that heretofore calks have 30 been removably secured to horseshoes by means of screw-threaded extensions. I desire, however, to obtain a greater bearing-surface and stronger means of support, and hence greater efficiency and durability, by 35 means of the improved form of construction embodied in this invention.

A further object of the invention is to utilize the narrow edge of the flange to form teeth for immediate use, such as employment 40 on ice or slippery roads, which would not injure the shoe for other employment.

A further object is to form an inclosure or chamber within which toe-weights can also be attached in speeding horses in place of 45 visible weights attached to the outside of the hoof.

A further object is to form an inner chamber in which plastic substances containing moisture or medicated foot-packs can be 50 applied to the frog and sole and quarters of the foot of a horse with dry or crippled feet, or to give frog-pressure to the frog of the foot when necessary to contract the foot and retain the packing while the horse is being 55 driven on the road or at work without dan-

ger of its falling out of place, and thus relieve the suffering animal from fever and distress and shield it from dirt and to prevent the shoe from balling with snow consequent upon the adhesion of snow between the inner edges 60 of the shoe and foot.

Another object is to form a channel or receptacle for a cushion to relieve the jar upon the hoof, which is particularly great upon pavements or race-tracks. 65

This construction avoids the application of rubber directly to the foot, as is the case in the use of rubber pads covering the whole surface of the foot, as now in use, which if left on the foot too long retard the natural 70 growth of the hoof and cause the frog of the foot to decay, and also the cushion is not punctured by the nails which attach the shoe to the foot and is not in contact with the ground, hence is more durable and less injurious to the horse. It can also be renewed 75 at any time without removing the shoe from the foot.

The packing is also inclosed, so that it can be of any shape or elastic material. 80

I accomplish these objects and obtain such advantages as have heretofore been described or may appear hereinafter by means of the forms of construction and combination and arrangement of parts as are described in 85 the following specifications, illustrated in the accompanying drawings, and are specifically pointed out in the claims.

In the accompanying drawings, Figure 1 is a plan view of a combined shoe and casing 90 embodying the general features of the invention. Fig. 2 is a longitudinal section therethrough, showing a plate with angular flange or leg, removable calks secured to the vertical flange, and a bottom plate and hinged 95 door or keeper designed to receive and retain moist or medicinal substances in contact with the foot. Fig. 3 is a plan view of this plate and hinged keeper. Fig. 4 is a perspective view of one of the heel-calks. Fig. 100 5 is a similar view of the toe-calk, and Fig. 6 is a transverse section of this shoe and casing, showing an inner tread-plate to which the calks are attached and an elastic cushion interposed between the casing-plate and the 105 inner tread-plate. Fig. 7 is a plan view of a similar shoe and casing having two vertical flanges or legs. Fig. 8 is a central longitudinal section therethrough. Fig. 9 is a transverse section thereof; and Fig. 10 is a side 110

elevation of a shoe and casing, showing teeth filed in the narrow edges suitable for use on ice.

In these figures, 1 is a flat plate of horse-shoe form, on which the foot rests, and is provided with nail-holes 2 for securing the shoe to the foot in the usual way. This plate is provided with a vertical leg or flange 3 on the outer side and in Figs. 7, 8, and 9 is shown 5 with a similar inner flange 4, thus forming combined shoe and casing, as previously stated. This vertical flange forms a support for calks 5 and 6 inclosed therein, which can therefore have any amount of needful bearing- 10 surface on the casing and can be made much larger and stronger than if attached to a thin shoe alone. One method of attaching these calks is shown in Figs. 1 and 2, 3 and 4, where the heel-calks 5 are shown provided 15 with lateral lugs 7, which enter holes 8 in the flange. Bolts 9 are used to complete the fastening. The front or toe calk 6 is bolted to the flange by bolts 10 and is provided with a shoulder 11, on which the edge of the flange 20 rests, so as to protect the plate 1 and hold the calk more securely. 25

In Figs. 6, 7, 8, and 9 an inner shoe-shaped plate 12 forms the tread or calk plate, and to it the calks are attached or are formed integrally therewith. This plate 12 can readily 30 be removed, since it is only secured by pins or screws 13, inserted in the vertical flange or flanges to prevent its dropping out. The advantage of this method of mounting the calks 35 is found in the opportunity thus afforded for interposing a spring or cushion 15 between the outer plate 1 and inner plate 12.

The cushion can be metallic or formed of any suitable elastic substance, such as rubber, and will not interfere in this position 40 with the driving of the nails in the shoe. An advantage is found in the location of the cushion between two plates, the upper one being the nail-plate, since if the nails penetrate the rubber and lower plate, as now often used, the constant compression of the rubber will lessen the distance between the foot and plate and the nails will work loose or break off. 45

50 A bottom plate 16 is shown secured in any suitable manner, as by screws 17, as in Figs. 1, 2, 7, 8, and 9, or between the cushion 12 and plate 1, as shown in Fig. 6. This bottom plate serves, with the casing, to form an inclosed chamber in which moist clay or medicated packing of any kind can be inclosed and kept in constant contact with the foot for any length of time. This material thus protected will retain its efficiency for some time, 55 even if the horse is in motion.

A door or keeper 19, hinged to the plate at 20, gives access to this chamber for packing or renewal and also permits the clay or other packing to be continued upward around the 60 horse's heel. A turned-down extremity 21

of the hinge-strap serves to retain a strap passed about the horse's hoof and keep the door shut.

In Figs. 1 and 3 side arms 22 engage the heel-calks and prevent the bottom plate, with 70 door attached or detached, from dropping down.

Fig. 10 shows how teeth 30 can be filed in the edges of the casing for temporary use on ice or slippery floors, which can easily be re-sharpened on the foot, since the casing is 75 formed of soft material.

In connection with these forms of horse-shoe an expansion-spring 25 is shown inserted between the heel-calks to prevent the contraction of the outer shell of the hoof from pressing upon the frog. This spring can be of any strength or tension to suit the requirements of the condition of each foot. 80

Having described the invention, what I 85 claim as new, and desire to secure by Letters Patent, is—

1. In a horseshoe, comprising a flat plate of horseshoe form, on which the foot is designed to rest, the said plate having a vertical 90 flange extending downwardly from its outer edge, and calks located underneath said plate and adjacent to the inner side of said flange, the front calk having a shoulder adapted to engage the lower edge of said flange, substantially as described. 95

2. A horseshoe, comprising a flat plate of horseshoe form, said plate being provided with an integral vertical flange on each edge, 100 said flanges forming a casing between them, and calks rigidly and detachably secured within said casing the front calk having a shoulder adapted to engage the lower edge of said flange, and the rear calks having pins adapted to enter openings in said flange. 105

3. A horseshoe comprising a curved flat plate having an integral vertical flange on its outer edge and perforated for attachment to the foot, calks arranged underneath the plate, a curved plate connecting the calks together and removable therewith, and a cushion of flexible material between said upper and lower plates. 110

4. The combination with a curved and perforated shoe-plate and vertical flanged casing 115 therefor, substantially as described, of calks arranged within the casing, a curved plate within the casing to which said calks are attached, a cushion between the calk-plate and shoe-plate and a retaining device for the calk-plate, substantially as described. 120

5. The combination with a curved and perforated shoe-plate, and vertical casing therefor, substantially as described, of a bottom plate secured to said casing below the shoe-plate and a heel-plate hinged to the bottom plate, substantially as described. 125

6. The combination with a curved and perforated shoe-plate, and vertical casing therefor, substantially as described, of a bottom 130

plate within the casing extending from one side of the shoe to the other, a heel-plate hinged to the bottom plate, and a transverse spring-bar engaging opposite sides of the casing and extending across the open end of the shoe, substantially as described.

5 7. The combination with a curved and perforated shoe-plate, and vertical casing therefor, of calks within the casing, a bottom plate between the inner sides of the casing, a hinged heel-plate, a spring-bar extending

across the opening in the shoe at the heel and engaging said shoe-plate at each end, and means for supporting said hinged heel-plate in the raised position, substantially as described. 15

In testimony whereof I hereunto set my hand this 23d day of February, 1906.

JOHN D. OLCOTT.
